Primary Examiner—Paula A. Greene(74) *Attorney, Agent, or Firm*—Fish & Richardson P.C.**CLAIM**

The ornamental design for a chassis for a currency acceptor system, as shown and described.

DESCRIPTION

FIG. 1 is a front perspective view of a chassis for a currency acceptor system according to our design; the undisclosed rear and bottom are not part of the claimed design; and,

FIG. 2 is a side elevational view of a chassis for a currency acceptor system, the undisclosed rear and bottom are not part of the claimed design.

The broken lines are included for the purpose of illustration and form no part of the claimed design.
